(57) **CLAIM**

The ornamental design for a handle, as shown and described.

DESCRIPTION

FIG. 1 is a perspective view of my new design of the handle shown in a folded condition.

FIG. 2 is the front view of the handle of FIG. 1 shown in an open condition, the rear view being the same.

FIG. 3 is the right side view of the handle of FIG. 2, the left side view being the same.

FIG. 4 is the top view of the handle of FIG. 2, the bottom view being the same.

FIG. 5 is a perspective view of a second embodiment of FIG. 1 shown in a folded condition.

FIG. 6 is the front view of the handle of FIG. 5 shown in an open position, the rear view being the same.

FIG. 7 is the right side view of the handle of FIG. 6, the left side view being the same; and,

FIG. 8 is the top view of the handle of FIG. 6, the bottom view being the same.

The broken lines of the handle are for illustrative purposes only, and form no part of the claimed design.
